ATTORNEY

UNITED STATES PATENT OFFICE

GEORGE ERVING THOMPSON, OF OAKLAND, CALIFORNIA

AUTO TABLE

Application filed July 13, 1926. Serial No. 122,196.

My invention relates to improvements in adjustable shelves for automobiles, and it consists in the combinations, constructions, and arrangements hereinafter described and claimed.

An object of my invention is to provide an adjustable shelf which is an improvement over that form of device shown in my co-pending application filed June 8th, 1926,

Serial Number 114,394.

In my present invention I provide novel means for reinforcing two movable parts, this means also guiding the parts in their movement.

Other objects and advantages will appear in the following specification, and the novel features of the invention will be particularly pointed out in the appended claim.

My invention is illustrated in the accompanying drawing, forming a part of this application, in which—

Figure 1 is a side elevation of the device,

Figure 2 is a bottom plan view of the device,

Figure 3 is a section along the line of 3—3

Fig. 2, and

Figure 4 is a section along the line of 4—4 of Fig. 2.

In carrying out my invention I provide a pair of flat table members 1 and 2. These members may be of any desired width and length. The member 1 has an angle iron 3 secured thereto, while the member 2 has an angle iron 4, similar to the angle iron 3, secured thereto.

Since the angle irons 3 and 4 are similar, an explanation of the construction of the angle iron 3 will be sufficient. It will be noted from Figure 2 that the angle iron 3 extends across the width of the member 1 and is secured thereto by means of screws 5.

The side 6 of the angle iron 3 abuts against the edge of the member 1 and is secured in place by means of screws 7. The side 6 is of the same length as the width of the member 1.

The side 6a has projections 8 which extend beyond the side 6, and the projections are bent at right angles at 8 and 9 to overlie the edges of the members 1 and 2, and the opposite member. The projections 8 form 50 guiding channels for the parts 1 and 2. This permits movement of one part with respect to the other whereby the shelf may be extended.

In Figure 4 I show the parts 1 and 2 as 55 being spaced from each other by means of strips 10.

The members 1 and 2 are limited in their outward movement by means of a pin 11. The free ends of the members 1 and 2 are 60 covered with a felt pad or a pad made of other suitable material.

From the foregoing description of the various parts of the device, the operation thereof may be readily understood. In Figure 1 I show the device as being operatively applied to the movable window panes 13 of an automobile (not shown). Pins 14 are secured to the members 1 and 2 for providing channels which receive the upper edges of 70 the window panes 13.

The window panes 13 are adapted to be moved by the usual mechanism (not shown). By using this mechanism, the device may be raised or lowered to the desired position. 75 The shelf is especially adapted to be used as a table or as a supporting device, for handbags, valises or other articles. When handbags and other articles are carried by the device, the window panes 13 may be 80 raised so as to hold the handbags etc. against the top of the car. In this way the devices are held in place and are disposed in a position where they will not interfere with the passengers of the car. 85

The angle irons prevent the sagging of the members when the members are in extending position.

I claim:

An extension table having a top composed 90

of two movable board members, bracing and guiding means for securing said members together, said means comprising a pair of angle irons, each of which is secured to an end of each member, each angle iron extending completely across the member to which it is attached and downwardly so as to embrace the other member, each angle iron having a flange extending downwardly therefrom covering the end of the member to which it is attached.

5 In testimony whereof I affix my signature.

GEORGE E. THOMPSON.
